SHEET-FEEDING MECHANISM.

1,348,254.

Specification of Letters Patent.

Patented Aug. 3, 1920.

Original application filed September 16, 1919, Serial No. 324,072. Divided and this application filed January 27, 1920. Serial No. 354,325.

To all whom it may concern:

Be it known that I, BURT F. UPHAM, a citizen of the United States, residing at Boston, in the county of Suffolk and State of Massachusetts, have invented certain new and useful Improvements in Sheet-Feeding Mechanism; and I hereby declare that the following is a full, clear, and exact description thereof, reference being had to the accompanying drawings, which form part of this specification.

This application is a division of my application for printing press, filed September 16, 1919, Serial No. 324,072; and has particular reference to feeding the sheets to printing presses, and the like.

The object of this invention is to provide a sheet feeding mechanism whereby the sheets may be fed quickly and smoothly to the grippers of the impression cylinder, or other sheet taking means, of a printing press, or machine for operating upon sheets, and its objects are—(1) to insure that the sheets will be cleared from wrinkles as they are fed to the printing mechanism; and (2) to enable the sheets to be fed alternately from two feed tables so that the sheets can be properly supplied to a rapidly operating printing or other mechanism, and ample time be given for each sheet to be properly registered upon its feed table before being taken therefrom.

One practical embodiment of the invention is illustrated diagrammatically in the accompanying drawings, and a description thereof will enable others skilled in the art to understand and utilize the same; and the essentials of the invention and novel combinations and constructions of parts for which protection is desired are all set forth in the appended claims.

In said drawings Figure 1 represents diagrammatically a longitudinal sectional elevation of one form of sheet feeding mechanism embodying the invention.

Figs. 2 and 3 are diagrammatic views illustrating different positions of sheets in transfer from the tables to the taking mechanism.

For convenience the invention will be described as applied to a rotary sheet printing press, such, for instance, as illustrated in my aforesaid application.

The plate-cylinders 1 and 2 (indicated in Fig. 1) are adapted to carry printing surfaces of any suitable kind, and are supplied with ink from fountains F and F', respectively, in the usual manner. An impression-cylinder 1^a coöperates with plate cylinder 1, and an impression-cylinder 2^a coöperates with plate-cylinder 2. The impression-cylinders 1^a, 2^a are arranged close together and substantially intermediate the plate-cylinders 1 and 2.

In the example shown instead of the impression-cylinders being provided with grippers to handle the sheets, the sheets are carried through the successive printing couples to the point of delivery by means of traveling gripping devices, preferably mounted upon an endless carrier 3, which may be of any suitable construction.

The sheets to be printed are fed to the grippers 3^a at any convenient point, and presented thereby successively to the plate-cylinders of the printing couples. The aforesaid parts are fully explained in my application above referred to; but it should be clearly understood that the present invention is not limited to use with any particular type of printing press, or other mechanism for operating upon sheets.

In the example shown the sheets are fed to the grippers 3^a at the point T, adjacent the cylinder 1, by means of novel feed mechanism adapted to alternately present sheets S from a table 6, and sheets S' from a table 6^a, to the grippers on the endless carrier.

The feed tables 6, and 6^a, may be of any suitable construction and the sheets may be fed into properly registered positions thereon either by hand, or by any of the well known or other suitable mechanical devices for feeding sheets on said tables. The sheets can be properly positioned on the table 6 against the usual stops or gages 6^b, and the sheets can be positioned on the table 6^a against the usual stops or gages 6^c.

As shown the sheets are taken from table 6 by grippers 5^e on a cylinder or reel 5^b; and in the example shown, the grippers are operated to take a sheet from the table on every other revolution of cylinder 5^b.

The sheets are taken from the tables 6^a by grippers 5^e on a cylinder or reel 5^d having the same peripheral speed as cylinder 5^b.

In the example shown cylinder 5^a is smaller than cylinder 5^b and would make two revolutions to each revolution of the cylinder 5^b; and the grippers 5^c would therefore be 5 operated to take a sheet from the table 6^a on every fourth revolution of cylinder 5^a.

The parts should be so arranged and timed that the cylinder 5^b will take a sheet S from the table 6 and deliver it to the printing or 10 other taking mechanism, (or to transfer roll 5, hereinafter referred to) at the point T'; and during this rotation of cylinder 5^b, grippers 5^c on cylinder 5^a take a sheet S' from table 6^a in time to transfer this sheet to the 15 grippers 5^c on cylinder 5^b after they have released the sheet S, and during the first revolution of cylinder 5^b (see Fig. 1), and then the sheet S' is carried by cylinder 5^b and delivered during the second revolution 20 of cylinder 5^b to the printing or other taking mechanism (or to the transfer cylinder 5) at the point T'.

During such second revolution of the cylinder 5^b, the grippers 5^c do not take 25 any sheet from table 6 nor from cylinder 5^a nor do grippers 5^c take a sheet from table 6^a; but after cylinder 5^b has surrendered the sheet S' at the point T', and during the next (third) revolution of such cylinder 30 grippers 5^c are carried to take a sheet S from table 6, and grippers 5^c to take a sheet S' from table 6^a.

During such third revolution of cylinder 5^b grippers 5^c take a sheet S from table 6 35 and deliver it at the point T'; and then take a sheet S' from the cylinder 5^a. Thus during each revolution of the cylinder 5^b, a sheet S, or S', is delivered to the printing or other taking mechanism from the 40 table 6, or 6^a, the sheets being alternately fed from such tables.

Preferably I do not deliver the sheets direct from cylinder 5^b to the printing mechanism unless the circumference of the 45 cylinder 5^b is large enough to insure that the whole sheet will be bent upon the periphery of this cylinder before it is taken by the printing mechanism; and if the sheets were large this would require cylinder 5^b to be of very large diameter; and I therefore preferably provide an intermediate transfer cylinder or roll between the cylinder 5^b and the printing mechanism.

As shown a transfer cylinder or reel 5 55 is provided having grippers 5^a adapted to take sheets at the point T', from grippers 5^c of the feed cylinder 5^b, which alternately supplies sheets S and S' from table 6 and 6^a as described.

60 As the cylinder 5, or printing or other taking mechanism, receives sheets alternately from tables 6 and 6^a ample time is given for positioning the sheets S, S' on the tables 6, 6^a, against the respective sheet stops 6^b and 6^c; and twice as much time 65

is allowed for positioning the sheets on the respective feed tables as would be permitted if all the sheets were fed from one table.

Devices of any suitable kind for operating the grippers 5^a, 5^c, and 5^e, should be 70 provided at the points T, T', T², T³ and T⁴, and so timed that sheets S and S' are alternately taken from the tables 6 and 6^a and delivered in alternation to the printing mechanism as described; such gripper operating devices being well understood are not 75 illustrated.

A great deal of trouble has been heretofore experienced in printing large sheets of paper on presses operating at high speeds, 80 so by wrinkles, such wrinkles frequently causing defective printing and spoiling sheets; so that for high grade work, when operating on sheets that have been slightly wrinkled, it has been necessary to reduce the 85 speed of the press to obtain satisfactory results.

I have found that if the sheets can be 90 reversely bent throughout before being seized by the cylinder grippers that wrinkling thereof will be prevented, and the sheets will be smoothed out so that the press can be operated at high speed and produce good printing on such sheets.

I have furthermore found that the 95 entire sheet should be reversely bent before it is seized by the cylinder grippers, for if a long sheet is taken by the cylinder grippers the tail-end portion of the sheet is only bent as it passes between the impression and 100 plate cylinders; and such tail-end portion of the sheet is apt to be wrinkled as such portion would not be smoothed out prior to being gripped between the printing and impression surfaces. Therefore I preferably 105 provide at least two coöperating cylinders or reels to transfer the sheets from the tables to the impression cylinder or other taking devices, to insure that the sheets will be reversely bent between the table and 110 the impression cylinder. Such reverse bending of the sheets has the desirable effect of smoothing out the wrinkles and causing the sheets to pass uniformly and smoothly to and through the printing mechanism. 115

In the example shown, it will be seen that the sheets S are first bent to the right around cylinder 5^b and then bent to the left around the reel 5. And the sheets S' are bent in passing around cylinder 5^a and 120 reversely bent in passing around cylinder 5^b; and are again bent in passing around the reel 5. If only one table 6^a was employed the cylinder 5^b might deliver direct to the printing mechanisms at the point 125 T'; but if only one table 6 is employed then the intermediate transfer cylinder 5 is important in order to reversely bend the sheets fed from table 6.

I consider the provision of means for re- 130

versely bending the sheets between the feed table and the impression cylinder so as to eliminate wrinkles and smooth out the sheets a very important practical improvement in the art of printing; I also consider the means shown for feeding sheets alternately from the tables 6 and 6^a a novel and valuable improvement in the art.

What I claim is:

- 10 1. In combination, a sheet supply; and printing mechanism; with a gripper cylinder adapted to take sheets from the supply and a second gripper cylinder adapted to take sheets from the first gripper cylinder and deliver same to the printing mechanism; whereby the sheets are reversely bent between the table and the printing mechanism.
- 20 2. In combination printing mechanism; and a feed table from which the sheets are to be fed; with a gripper cylinder for removing sheets from the table; and a second gripper cylinder receiving sheets from the first cylinder and transferring same to the printing mechanism; whereby the sheets are reversely bent between the table and the printing mechanism.
- 30 3. In combination mechanism for operating upon sheets; and a pair of feed tables; with a gripper cylinder for feeding sheets from one table, and a smaller gripper cylinder for feeding sheets from the second table to the first gripper cylinder; whereby the sheets are alternately supplied to the operating mechanism from the respective tables.
- 40 4. In combination a printing mechanism; and a pair of superposed feed tables; with a gripper cylinder for feeding sheets from the lower table, and a smaller gripper cylinder for feeding sheets from the upper table to the said gripper cylinder; whereby the sheets are alternately delivered from the tables, substantially as described.
- 50 5. In combination a sheet printing mechanism; and a pair of feed tables; with three gripper cylinders whereby the sheets are alternately transferred from the said tables to the printing mechanism and each sheet reversely bent between the tables and the printing mechanism.
- 60 6. In combination a printing mechanism; and a pair of superposed feed tables; with a first gripper cylinder for feeding sheets from one table; a second gripper cylinder for feeding sheets from the second table to the first gripper cylinder; and a third gripper cylinder adapted to receive sheets from the first gripper cylinder and transfer same to the printing mechanism; the cylinders be-

ing so arranged that the sheets are reversely bent between the feed table and the printing mechanism.

7. In combination a sheet supply, and means for operating upon sheets; with means for transferring sheets from the supply to the operating means and reversely bending the sheets between the point where the sheets are taken from the supply and the point where the sheets are received by the operating means.

8. In combination, a table from which sheets are to be fed; and mechanism for operating upon sheets; with a set of cylinders for removing sheets from the table and transferring same to the operating mechanism, whereby the sheets are reversely bent between the point where the sheets are taken from the table and the point where the sheets are received by the operating mechanism.

9. In combination mechanism for operating upon sheets; and a pair of feed tables; with a set of cylinders and co-acting means whereby the sheets are alternately transferred from the said tables to the operating mechanism and are reversely bent between the points where the sheets are taken from the tables and the point where the sheets are received by the operating mechanism.

10. In combination a sheet printing mechanism; and a feed table; with three cylinders and co-acting means whereby the sheets are transferred from the said table to the printing mechanism and each sheet reversely bent between the table and the printing mechanism.

11. In combination a sheet printing mechanism; and a pair of feed tables; with three cylinders and co-acting means whereby the sheets are alternately transferred from the said tables to the printing mechanism and each sheet reversely bent between the table from which it was taken and the printing mechanism.

12. In combination a printing mechanism; and a pair of superposed feed tables; with a first cylinder and co-acting means for feeding sheets from one table; a second cylinder and co-acting means for feeding sheets from the second table to the first cylinder; and a third cylinder and co-acting means adapted to receive sheets from the first cylinder and transfer same to the printing mechanism; each sheet being reversely bent between its feed table and the printing mechanism.

In testimony that I claim the foregoing as my own, I affix my signature.

BURT FROST UPHAM.
